(Cl. D48—24)

FIG. 1

FIG. 2

FIG. 3

Fig. 1 is a perspective view of a hand lantern showing my new design.

Fig. 2 is a side elevational view thereof with the battery fragmentarily shown for convenience of illustration.

Fig. 3 is a top plan view thereof.

Fig. 4 is a rear elevational view thereof with the battery fragmentarily shown for convenience of illustration.

Fig. 5 is a reduced side elevational view thereof showing the lamp pivoted toward the opposite side.

Fig. 6 is a reduced side elevational view showing the lamp pivoted upward.

Fig. 7 is a reduced sectional view taken on the line 7-7 of Fig. 2.

Fig. 8 is an enlarged sectional view taken on the line 8-8 of Fig. 7.

The dominant features of my design reside in the portions shown in full lines.

I claim:

The ornamental design for a hand lantern, as shown and described.
